Primary Examiner—Peter M. Cuomo*Assistant Examiner*—Monica E. Millner*Attorney, Agent, or Firm*—William J. Ruano[57] **ABSTRACT**

A portable door lock operable from the inside of a door for selectively clamping or unclamping the door latch. Such door lock comprises two halves pivoted together centrally and having confronting serrated semi-circular openings at one end and screw means for selectively pivoting said halves at the other end.

1 Claim, 1 Drawing SheetFIG. 1

FIG. 2

FIG. 3

FIG. 4

1

PORTABLE DOOR LOCK

BACKGROUND OF THE INVENTION

Heretofore, no suitable portable door locks have been devised to prevent unauthorized unlatching of doors.

SUMMARY OF THE INVENTION

A portable door lock in the form of a pivotal clamp for clamping a door lock to prevent unauthorized unlocking.

BRIEF DESCRIPTION OF THE DRAWING

FIG. 1 is a top view;

FIG. 2 is a side elevational view; and

FIG. 3 is a bottom view of a portable door lock to prevent unauthorized unlatching.

FIG. 4 is a vertical cross-sectional view taken along line 4—4 of FIG. 2.

DESCRIPTION OF THE PREFERRED EMBODIMENT

Numerals 1 and 2 denote clamp halves pivotally mounted on hinge 3. A slotted screw 4 engages threads in end portions 5 and 6 to selectively pivot the clamp halves 1 and 2 to either bring the opposite ends together or to move them apart, depending upon the direction of rotation of the screw 4, either by the use of a screwdriver or by hand. Said opposite ends preferably are serrated at 7 and 8 to enable firm clamping of the door latch (not shown) which they are adapted to surround by merely sliding the clamp halves 1 and 2 through the space between a door and the adjoining

2

door frame, which space is about $\frac{1}{8}$ " wide, which restricts the width of the clamp halves to less than said space, such as to $\frac{1}{16}$ " wide.

In operation, when it is desired by the homeowner to clamp the door latch from the inside of the door, the portions of the clamp halves forward of the hinge 3 are inserted in the space between the door and the adjoining door frame while in the position shown in FIG. 2 and thereafter by turning screw in the direction to clamp the door latch, the serrated portions 7 and 8, the door latch is firmly held so as to prevent unauthorized unlatching.

While a screw 4 has been shown for effecting clamping of the door latch, equivalent means, such as a snap lock, cam or spring may be used instead for clamping and unclamping.

I claim:

1. A device for clamping a door latch from the inside of a door comprising a pair of clamp halves of a width of less than $\frac{1}{8}$ inch wide pivotally connected together by a central pivot, each clamp half having, at one end portion, a substantially semi-circular serrated opening which confronts another substantially semi-circular serrated opening of the other clamp half for surrounding and clamping said door latch when the portions of said clamp halves having said serrated semi-circular openings are projected through the space between a door and door frame, each clamp half at the other end portion, means for pivoting said clamp halves in either direction, comprising a pair of adjoining internally threaded circular portions and a screw for engaging said internally threaded circular portions for selectively clamping or unclamping said serrated semicircular openings.
